UNITED STATES PATENT OFFICE.

JOSEPH BAGNALL, OF NORTH ATTLEBOROUGH, MASSACHUSETTS, ASSIGNOR
TO ANTHONY H. BLISS, OF SAME PLACE.

DESIGN FOR A NECKLACE AND WATCH-CHAIN.

SPECIFICATION forming part of Design No. 31,544, dated September 26, 1899.

Application filed August 9, 1899. Serial No. 726,727. Term of patent 8½ years.

To all whom it may concern:

Be it known that I, JOSEPH BAGNALL, of North Attleborough, Bristol county, Massachusetts, have invented and produced a new and original Design for a Necklace and Watch-Chain, of which the following is a specification, reference being had to the accompanying drawing, forming a part thereof.

In the drawing the figure is a plan view of the necklace and chain embodying my design.

As shown, the leading or material feature is in making the necklace double at the rear and single across the front, the double lines being indicated at A and the single at D.

The single line carries the locket C. The double lines terminate at the points E, and from thence single lines E' extend, being joined at the point F, the lines E' E' and F making

practically a V shape. The double lines A are held together at the rear by an ornamental piece G. The parts E' present generally a V shape, with their upper ends connected by a curved portion, while adjacent to this curved portion and reaching down to the upper ends of the links of the V a circular figure formed by a line of chain is located. The double lines extend from the upper part of the V along the sides of the neck portion of the chain and around the back of the same.

What I claim is—

The design for a necklace and watch-chain herein shown and described.

JOSEPH BAGNALL.
